COMBINED ASH TRAY AND SAFETY MEANS

Niels Gerner, Euclid, Ohio

Application June 3, 1942, Serial No. 445,557

7 Claims. (Cl. 131—235)

This invention relates to a combined ash tray and safety means for use by smokers. The device is shown as adapted to hold and operate on cigarettes and cigars of similar size and to hold ashes resulting from the smoking or burning thereof, but may be shaped to hold and operate on cigars of standard size.

The device is constructed to provide a closed chamber into which the lighted end of a cigarette is inserted, so that as soon as the oxygen in the air in the chamber is consumed due to its combination with the burning portion of the cigarette, combustion ceases. By making the chamber relatively small, so that it contains a small volume of air, combustion will cease in a relatively short period of time, to eliminate danger of fire, but by increasing the size of the chamber, the cigarette will smoulder and remain lighted sufficiently long to permit the smoker to lay the cigarette down with its lighted end inserted in the chamber, while attending to some detail, and then again remove it for continued use, without being forced to re-light the cigarette. In this connection, it will be observed that when the cigarette is positioned with its lighted end in the chamber, smouldering, so long as such end remains lighted, is restricted to that portion of the tobacco which is in a combustible state, so that waste due to continued burning is eliminated. This arrangement is advantageous where the smoker has many interruptions. It is also advantageous as the smoker is well aware of the fact that in the event his interruption is delayed or the cigarette is forgotten, it will eventually cease to burn and hence avoid danger of fire. The construction is also advantageous since it provides an enclosure for the lighted end of a cigarette so that such end cannot be accidentally or otherwise touched.

One object of the invention is to provide an improved device for holding lighted or burning cigarettes, provided with safety means for stopping the burning thereof and/or snuffing out the burning portion of the tobacco, whereby fire hazards are eliminated.

Another object of the invention is to provide an improved device of this character having a receptacle for ashes, a support for a cigarette and a chamber associated with the support so as to receive the lighted end of the cigarette whereby further burning thereof is arrested.

Another object of the invention is to provide an improved device of this character having a receptacle for ashes, a support for a cigarette, a chamber associated with the support and ar-

5 ranged to receive the lighted end of the cigarette and means in the chamber for varying the size of the chamber to increase or decrease the volume of oxygen therein; whereby further combustion is arrested and snuffed out.

A further object of the invention is to provide an improved ash tray and safety attachment therefor of simple construction.

Other objects of the invention will be apparent 10 to those skilled in the art to which my invention relates from the following description taken in connection with the accompanying drawings, wherein

Fig. 1 is a plan view of a device embodying my 15 invention.

Fig. 2 is a side elevation.

Fig. 3 is a section on the line 3—3 of Fig. 1.

Fig. 4 is a section on the line 4—4 of Fig. 3.

Fig. 5 is a plan view with parts broken away, 20 showing a modified form of construction.

Fig. 6 is a plan view with parts broken away, showing a different embodiment of the invention.

Fig. 7 is a section on the line 7—7 of Fig. 6.

Fig. 8 is an elevational view of the partition 25 walls.

In the drawings, 1 indicates as an entirety a base which may be formed of or coated with non-inflammable material. It is desirable to form the parts of the device from or coated with a material incapable of being attacked by tobacco which is in a state of combustion, so that such parts may be readily cleaned from time to time. To secure these results I prefer to form the parts of glass which may be colored or decorated in 30 any desired manner. In the preferred arrangement, the base 1 may be opaque or semi-opaque, whereas the cap (later referred to) for the snuffing chamber may be transparent, whereby the smoker can determine whether he has positioned

40 the lighted end of the cigarette therein and whether the cigarette is still lighted in the event he wishes to remove it. The base 1 is preferably of circular contour. In this form of construction the base 1 is shaped to form a centrally disposed recess 2 and an ash tray 3 around portions of the side walls of the recess 2. 4 indicates a support extending from one side of the recess 2 to the periphery of the base 1 and formed with a concaved groove 4' to receive and hold a cigarette, the side walls of the recess 2 and ash tray being cut-away at 2', 3', respectively, in 45 alined relation to the groove 4', so that when a cigarette is positioned on the support 4 its inner end may extend into the recess and its outer end outwardly beyond the periphery of the base

50 55

1 depending upon the length of the cigarette. 5 indicates a cap for the recess 2 to form a smouldering or snuffing chamber 5a to permit of access to the recess 2. The cap 5 removably fits over the recess. By preference the side walls of the recess 2 extend above the support 4 to form a seat 2a for the cap, the inner wall of the latter being rabbeted, as shown, to fit over the seat 2a. At one side, the cap 5 is cut away as shown at 5b, which co-operates with the cut-away 2' to form a round opening 5b' of a size to snugly fit the inserted end portion of a cigarette, so that when the cap 5 is in position and a cigarette is placed on the support 4 with its inner end portion inserted into and through the opening 5b' formed by the cut-aways 2', 5b, the recess 2 and cap 5 entirely close the chamber 5a, whereby further combustion of the lighted cigarette will depend on the amount of oxygen present in the air in the chamber 5a.

Means are provided for alining the cut-away 5b with the support 4 to facilitate proper positioning of the cap 5 when it is replaced. These means are preferably provided for by the interiorly rabbeted wall of the cap 5, whereby its marginal edge extends slightly below the plane of the support 4, so that the opposite sides of the cut-away 5b engage the sides of the support and accordingly determine the operative position of the cap 5 as well as prevent it from rotating on its seat 2a into a position disaligned with the support 4.

The chamber 5a may be of any predetermined size to regulate the approximate period of time it will take for combustion of the lighted cigarette end to entirely cease. However, by providing in the chamber 5a a rotatable member indicated as an entirety at 6, as shown in Fig. 5, the size of the snuffing chamber (that is, its volumetric capacity) may be changed. The member 6 consists of a diametrical wall 6a forming with the walls of the chamber 5a a sub-chamber 6a' and a radially extending wall 6b disposed at an inclined angle to the wall 6a, forming with the latter wall and walls of the chamber 5a sub-chambers 6b', 6b'', which differ in size from each other as well as being smaller than the chamber 6a'. By rotating the member 6 it will be apparent that any one of the chambers 6a', 6b', 6b'' may be alined with the opening 5b'. The walls 6a, 6b, are preferably integral and throughout their end edges closely fit the inner walls of the recess 2 and cap 5. I provide an opening 5b' in operative relation to each chamber and a support 4 alined with each opening 5b', so that each and all of the chambers may be utilized.

Figs. 6 and 7 illustrate an embodiment of the invention wherein the base 1 is provided with four grooved supports 4 disposed at right angles to each other and extending from the recess 2 outwardly. In this arrangement, I provide a partitioning device indicated as an entirety at 6x having four walls 6x' disposed at right angles to each other, but each arranged to engage the side walls of the recess 2 in a plane substantially midway between two of the supports 4, whereby each wall 6x' and one of the adjacent walls 6x' form a space 6'' related to the inner end of each support 4. 7 indicates a removable cap which fits the upper end walls of the recess 2 as already set forth. The side wall of the cap 7 is formed with cut-aways 7a spaced 90 degrees therearound to form with the grooves of the supports 4 openings each arranged to snugly fit a cigarette when the latter is projected through the opening. In

this form of construction, the end edges of the walls 6x' closely engage the inner walls of the cap 7 as well as the inner walls of the recess 2, so that when a cigarette is positioned on any one of the supports 4 with its lighted end projected through the opening 7a alined therewith into the adjacent space or chamber 6x'' the latter is entirely closed to prevent the escape therefrom of air, so that as soon as the combustion of the lighted end consumes the oxygen content of the air in the space, further combustion will cease.

The device 6x is formed separate from the walls of the recess and removable therefrom.

Due to the fact that the chamber or space into which the lighted cigarette end is inserted will be closed by the latter, smoke and fumes generated therein cannot escape into the surrounding atmosphere.

Where the cap is formed of transparent material, ash accumulation in the space or chamber can be readily observed to determine whether such accumulation should be removed.

To those skilled in the art to which my invention relates many changes in construction and widely differing embodiments and applications of the invention will suggest themselves without departing from the spirit and scope of the invention. My disclosures and the description herein are purely illustrative and are not intended to be in any sense limiting.

What I claim is:

1. A combined ash tray and safety means comprising a device having a recess, a tray for ashes outwardly of said recess, and a grooved support for a cigarette or the like leading from the upper edge of the side wall of said tray to the upper edge of the side wall of said recess, and a cap for said recess seated on the side wall thereof and forming with said recess a chamber, the side wall of said cap being formed with a cut away alined with the groove at the inner end of said support to form an opening leading into said chamber to permit the inner lighted end of a cigarette to be projected through the opening into said chamber, the size of said opening approximating that of the cigarette, whereby when a cigarette is placed on said support and its inner end is projected through said opening said chamber is closed to prevent the intake of air thereinto.

2. A combined ash tray and safety means as claimed in claim 1 wherein is provided within said chamber a removable partition the peripheral edges of which fit the inner walls of said chamber to sub-divide said chamber into a plurality of sub-chambers.

3. A combined ash tray and safety means as claimed in claim 1 wherein is provided within said chamber a member consisting of a plurality of connected together angularly related partitions the peripheral edges of which fit the inner walls of said chamber to divide said chamber into a plurality of sub-chambers, said member being rotatable in said chamber.

4. A combined ash tray and safety means comprising a device having a centrally disposed recess, a tray for ashes surrounding said recess, and a plurality of grooved supports for cigarettes or the like leading from the upper end of the side wall of said tray to the upper end of the side wall of said recess, a cap seated on the side wall of said recess and forming therewith a chamber, the side wall of said cap being formed with cut aways each arranged to aline with the groove at the inner end of one of said supports to form an opening to permit the lighted end of a cigarette

to be projected through the opening into said chamber, and partitions within said chamber, the peripheral edges of said partitions being shaped to fit the inner walls of said chamber to divide it into sub-chambers, one for each of said openings, the size of each said opening approximating that of the cigarette, whereby when a cigarette is placed on the adjacent support and its inner end is projected through said opening into the sub-chamber related thereto said sub-chamber is closed to prevent the intake of air thereinto.

5. A combined ash try and safety means as claimed in claim 1 wherein the opposite sides of the cut away formed in said cap engage the sides of said support to prevent disalignment of the opening therewith.

6. In a combined ash try and safety means, the combination of a device comprising a bottom wall having spaced inner and outer upstanding annular walls arranged to form a recess within said inner annular wall and an ash tray between said annular walls and a support extending between and connected at its opposite ends to said annular walls and arranged to support a

cigarette or the like, and a cap seated on said inner annular wall and forming with said bottom wall and said inner annular wall a chamber, said cap being formed with a cut away arranged to align with said support to form therewith an opening through which the lighted end of the cigarette when placed on said support may be projected into said chamber, the size of said opening approximating that of the cigarette, whereby when a cigarette is projected through said opening into said chamber the latter is substantially sealed to prevent the intake of air thereinto.

10 7. A combined ash tray and safety means as claimed in claim 1, wherein is provided within said chamber a member consisting of a plurality of connected together partitions angularly related to divide said chamber into a plurality of sub-chambers of different sizes, the peripheral edges of said partitions fitting and slidably engaging the inner walls of said chamber, whereby said member may be rotated to selectively relate each chamber to said opening.
